US00D758405S

(12) **United States Design Patent**
Cho et al.

(10) **Patent No.:** US D758,405 S
(45) **Date of Patent:** ** Jun. 7, 2016

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Tae Hyoung Cho**, Seoul (KR); **Hyung Chang**, Seoul (KR); **Ji Kyoung Kim**, Yongin-si (KR); **Yoon Jung Oh**, Seoul (KR); **Young Sun Shin**, Seoul (KR)

(73) Assignee: **Samsung Electronics Co., Ltd.**, Suwon-si (KR)

(**) Term: **14 Years**

(21) Appl. No.: **29/495,439**

(22) Filed: **Jul. 1, 2014**

(30) **Foreign Application Priority Data**

Jan. 3, 2014 (KR) 30-2014-0000487

(51) **LOC (10) Cl.** **14-04**

(52) **U.S. Cl.**

USPC **D14/486**

(58) **Field of Classification Search**

USPC D14/485-495; D10/15; D18/24-33
CPC G06F 3/0481; G06F 3/0482; G06F 3/0488

(57) **CLAIM**

We claim the ornamental design for a display screen or portion thereof with graphical user interface, as shown and described.

DESCRIPTION

The sole FIGURE is the front view of a display screen or portion thereof with graphical user interface showing our new design.

The dot-dash broken lines represent a boundary line and form no part of the claimed design. The evenly dashed broken lines represent a display screen or portion thereof and form no part of the claimed design. The evenly spaced dots illustrate the claimed design.
